UNITED STATES PATENT OFFICE

158,206

COMBINATION BOOKEND AND VASE OR SIMILAR ARTICLE

Arthur S. Leitner, Los Angeles, Calif.

Application February 6, 1948, Serial No. 144,333

Term of patent 7 years

(Cl. D33—3)

To all whom it may concern:

Be it known that I, Arthur S. Leitner, a citizen of the United States, residing in Los Angeles, in the county of Los Angeles, State of California, have invented a new, original, and ornamental Design for a Combination Bookend and Vase or Similar Article, of which the following is a specification, reference being had to the accompanying drawing, forming a part thereof.

I claim:

The ornamental design for a combination bookend and vase or similar article, substantially as shown.

ARTHUR S. LEITNER.
